UNITED STATES PATENT OFFICE.

WILLIAM L. DE GRAFF, OF HOMER, ASSIGNOR OF ONE-HALF TO WILLIAM B. LOVELAND, OF GRAND RAPIDS, MICHIGAN.

ROWING APPARATUS.

SPECIFICATION forming part of Letters Patent No. 367,338, dated July 26, 1887.

Application filed November 19, 1886. Serial No. 219,395. (No model.)

To all whom it may concern:

Be it known that I, WILLIAM L. DE GRAFF, of Homer, in the county of Calhoun and State of Michigan, have invented a new and useful Improvement in Rowing Apparatus; and I do hereby declare that the following is a full, clear, and exact description of the same.

My invention is an improvement in rowing apparatus of that class in which the oar-blade is fixed pivotally to the edge of the boat and is actuated by an independent hand-lever controlled by the oarsman, the connection between the two parts being such as will cause the oar to move forward or backward in unison with a similar motion of the hand-lever. The primary object of such devices is to enable the oarsman to sit facing the direction of movement of the boat, while the work performed by him will be similar in all its motions to that required when an ordinary oar is employed and the oarsman sits facing the stern.

In carrying out my invention in a practical way to meet the requirements of such an object, I aim to provide a combination of elements arranged in compact and simple form, which shall have the effect of multiplying the movement of the hand-lever to the oar-blade, so that a long stroke may be made with comparatively slight movement of the said lever.

My invention consists of a tilting frame supported upon the edge of the boat and carrying the pivoted oar and the operating hand-lever therefor, with peculiar and novel connections between the oar and said lever, whereby the desired increased movement of the blade is effected.

Further, my invention consists of an oar formed in two parts connected so that a partial rotary movement is permitted to the oar-blade for the purpose of "feathering" the same on return-stroke, and in novel devices, employed in combination with this form of oar, by which the tilting of the supporting-frame automatically controls the position of the oar-blade for the working and feathering stroke.

The invention further consists in the various details of arrangement and construction by which the principle involved may be embodied in a practically-working apparatus.

All the details will be fully described hereinafter, and pointed out particularly in the claims.

In the drawings, Figure 1 is a plan view of the device, the parts being in position to begin the backward stroke. Fig. 2 is a perspective view with the operating parts in their forward position.

In the drawings the oar-blade is represented at A and the operating hand-lever at B, both of these parts being pivotally secured at points 1 and 2, respectively, to the frame C. This frame is composed of the upper and lower bars, a b, the latter of which is adapted to be pivotally secured to the edge of the boat in a manner hereinafter referred to, whereby the whole frame, with the parts secured thereto, may be tilted, so that the oar-blade can be raised free from the water for the return-stroke. The oar-blade is formed of wood in the ordinary manner. The stock 3 is divided, as at 4, the portion carrying the blade being swiveled to a pivoted portion, 5, all of which will be hereinafter particularly referred to. A short arm, 4^a, of the pivoted portion 5 of the oar-stock, extends approximately at right angles to the main body of the oar, and to this arm connection from the operating hand-lever is made. As heretofore intimated, it is desirable to multiply the movement of this arm, and consequently that of the blade, relatively to the amount of stroke made by the hand-lever, and for this purpose a peculiar form of connection is employed. As shown in Fig. 1, an arm, 6, extends from the hand-lever at a point within its pivot toward the pivot of the blade, being braced by a suitable rod or bar, 6^a. A link, D, is pivoted in the extreme end of this arm at 8, and is connected at its opposite end to the arm 4^a of the blade, as shown at 7. It will be observed that the point 8 is at as great a distance from the pivot of the handle as the structure of the device will permit, and the path traversed by it will be within the path of the point 7.

Supposing the dotted lines to represent the paths traveled by the two pivots 7 and 8, and the parts to be in position shown in Fig. 1, now let the pivot 8 be moved along its path to the point 9 and the length of the link D be

measured off to intersect the path of the pivot 7. It will be seen that while the pivot 8 is moving to the point 9 the pivot 7 will have passed to the position, as at 10, which, it is 5 clear, is greatly in excess of the imparting motion of the hand-lever. Thus to give the oar-blade a movement of one-fourth on its pivot it necessitates a movement of the handle equal approximately to only one-eighth of 10 a circle. The bottom bar of the supporting-frame is provided with ears, between which supporting-standards from the side of the boat are adapted to fit, a pin passing through the parts to make a pivotal connection. By this 15 construction the oarsman is enabled to lift the oar from the water, so as to return it to its forward position for a new working stroke. By the arrangement shown all dead-centers are avoided and there is no lost motion between 20 the parts.

As before intimated, I desire to utilize the motion of the tilting supporting-frame for the purpose of automatically controlling the position of the oar relatively to the water—that 25 is to say, when the frame is tilted to raise the oar from the water, the swiveled part of the oar-stock is acted upon to incline the blade for feathering, and when the opposite movement of the frame takes place the operating 30 mechanism causes the oar-blade to assume a position at right angles to the surface of the water, so that the working-stroke will be rendered effective to the highest degree. The swiveled portion of the oar-stock is provided 35 with a ferrule or sleeve, *d*, adapted to receive the end of the pivoted portion 5, the latter having a suitable bearing-surface by which the oar-blade is steadied and prevented from having any undesirable movement. A laterally-extending slot, *m*, is formed in the ferrule, and into this a pin projects from the bearing, which answers the purpose of preventing any longitudinal movement of the ferrule and at the same time permits a rotary motion to the blade 40 within certain limits. The slot and pin bear such a relation to each other that when the pin is in one end of said slot the oar-blade will be sufficiently inclined for the feathering action; but when the parts are operated to 45 cause the opposite end of the slot to strike the pin the blade will be then in position for the working-stroke.

The rotary movement of the oar-blade is effected in the following manner: To any suitable standard secured to the boat-side an arm, *f*, is pivoted, the pivot being directly in the same vertical line with the pivot of the oar-blade. The arm extends parallel with the oar-stock, and is provided with a pivoted vertical 55 extension, *f'*, having rack-teeth formed thereon adjacent to the oar-stock. The oar-stock, or the ferrule secured thereto, is provided with a segment of a gear, *f*², with which the teeth on the pivoted arm *f* are adapted to mesh. 60 The pivoted arm is held to its position in relation to the oar-stock by means of an extension, *g*, projecting from the pivoted portion

of the stock, and it will thus be seen that, no matter whether the oar-blade be in its forward or backward position, the pivoted extension *f'* will be adjacent thereto, and its teeth will 70 always be in engagement with the segment on the oar-stock.

The arm *f*, however, has no movement other than the pivotal one referred to; for being supported upon standards entirely independent of the frame C, the tilting movement of the frame is not imparted to it. When, therefore, the oar is raised from the water, the teeth of the rack on arm *f* will give a partial rotation 80 to the ferrule and oar-stock and the blade will be inclined for feathering. Upon the opposite tilting of the frame and oar for the working-stroke the reverse operation of the arm *f* and oar-stock takes place and the blade assumes a suitable position for effecting the 85 propulsion of the boat. By pivoting the extension *f'* to the arm *f* and holding the same by the projection *g* the position of the rack is 90 made to conform to the path described by the segment when the frame is tilted. The rack-teeth, slot, and pin serve to hold the blade to either position it may have assumed.

I do not wish to limit myself to the precise 95 details of construction shown, as any slight variation therefrom would still be within the broad spirit of my invention.

I am aware that it is not new to provide extensions upon the hand-lever and the oar and connect these extensions by a link, and I therefore do not claim this construction broadly.

I claim as my invention—

1. In a rowing apparatus, and in combination, the pivoted oar, the arm *4*¹, extending approximately at a right angle therefrom, the 105 link pivoted at 7 to the said arm and at 8 to the end of an extension on the handle, the said pivot 8 being positioned so that it will describe a path between the path of the pivot 7 and the pivot of the oar, substantially as described.

2. In combination with the tilting frame, a hand-lever and a portion of the oar-stock pivoted to said tilting frame, the oar-blade swiveled to the pivoted portion of the oar-stock, the segment carried by the swiveled portion of the oar, and the rack carried by a pivoted support and engaging the segment, substantially as described.

3. In a rowing apparatus, and in combination, a tilting frame, and hand-lever and oar-stock pivoted thereto, a blade swiveled to the pivoted portion of the stock, and mechanism, substantially as described, supported independent of the tilting frame, engaging with the swiveled portion of the oar and operating the same when the frame is tilted in either direction, substantially as described.

4. In combination, the tilting frame and hand-lever, the pivoted oar-stock, the swiveled portion carried thereby, having a segment formed thereon, an arm pivoted to a support in vertical line with the pivot of the oar-stock, rack-teeth on said arm arranged to engage with

the segment, and means for keeping said arm in engagement with the segment, all substantially as described.

5. In combination with the tilting frame and hand-lever pivoted thereto, a portion of the oar-stock, also pivoted to the said frame, the swiveled portion of the oar, the segment thereon, the pivoted arm with rack-teeth, and the projection *g*, carried by the oar-stock, all 10 substantially as described.

6. In combination with the tilting frame and the hand-lever, the part 5 and the swiveled portion of the oar, the segment carried by the said swiveled portion, the rack in engagement 15 therewith, the ferrule having a slot, and the pin adapted to engage with the ends of said slot, substantially as described.

7. In combination, the tilting frame, the hand-lever, the pivoted portion of the oar- 20 stock, the swiveled portion carried thereby

provided with a segment, the pivoted arm *f*, situated near the oar-stock, the extension *f'*, pivoted thereto and having teeth adapted to engage with the teeth upon the oar-stock, and the arm *g* upon the oar-stock, all substantially 25 as described.

8. In combination, an oar pivoted to a frame, an arm, 4^a, formed thereon at the pivot extending approximately at right angles to the oar-stock, whereby a bell-crank action is provided, a hand-lever, and a connection between the same and the said arm 4^a, substantially as described.

In testimony whereof I have signed my name to this specification in the presence of two 35 subscribing witnesses.

WILLIAM L. DE GRAFF.
